UNITED STATES PATENT OFFICE.

SAMUEL M. TAYLOR AND ALBERT D. OSBORN, OF LOYALTON, CALIFORNIA, ASSIGNEES
OF ONE-FOURTH TO MALCOLM P. ARMSTRONG, OF RENO, NEVADA, AND R. E. MC-
ILROY, OF LOYALTON, CALIFORNIA.

ADVERTISING TOWER.

Application filed May 27, 1922. Serial No. 564,019.

To all whom it may concern:

Be it known that we, SAMUEL M. TAYLOR and ALBERT D. OSBORN, citizens of the United States, residing at Loyalton, in the county of Sierra and State of California, have invented certain new and useful Improvements in Advertising Towers, of which the following is a specification, reference being had to the accompanying drawings.

10 It is the purpose of the present invention to provide an apparatus of this character for the display of various advertisements, mounted upon an endless carrier which in turn is rotatably mounted on a tower, to 15 extend a considerable height, as an example of about fifty or sixty feet or possibly seventy feet in height.

Another purpose is the provision of an endless carrier, on which a plurality of 20 panels are pivotally mounted, containing advertisements upon either opposite faces, in order that they may be displayed from either side of the tower. For instance as 25 the panels move upwardly on one side of the tower, an advertisement may be displayed, and when descending different advertisements may be displayed on the opposite side of the tower.

Still another purpose is the provision of 30 means for guiding the various panels during their ascending and descending movements, in combination with means for shifting the lower parts of the panels, from one set of guides when ascending, to another set 35 of guides when descending.

A further purpose is the provision of an advertising tower illuminating at the top and bottom and on the opposite sides with different colored lights, in order to give 40 an effect of a rainbow display, whereby the advertisements are clearly visible at night, as well as in the day.

Still further, it is the aim to provide a motor driven endless carrier including the 45 advertising panels, with guides in the sides of the tower to guide the panels when ascending and descending, in combination with guy wires, for holding the tower in a perpendicular position.

50 It is to be understood that the particulars herein given are in no way limitative and that while still keeping within the scope of the invention, any desired modifications of

detail and desired proportions may be made in the apparatus according to circumstances. 55

The invention comprises further features and combination of parts, as will be herein-after set forth, shown in the drawings and claimed.

In the drawings:

Figure 1 is a vertical sectional view showing the advertising tower constructed in accordance with the invention, and showing the guy wires;

Figure 2 is a plan view of the same, also showing the guy wires;

Figure 3 is a view of the upper portion of the tower in side elevation, showing the panels in section, and showing the means for shifting the panels from one guide to another;

Figure 4 is a view of the lower portion of the tower showing a panel in section, and also the means for shifting the panel from one guide to another;

Figure 5 is a detail view of the mounting of a panel on the chain;

Figure 6 is a fragmentary detail perspective view of the upper portion of one of the standards of the tower;

Figure 7 is a fragmentary detail perspective view of the lower portion of one of the standards of the tower.

Referring to the drawings, 1 designates the tower as a whole, which comprises oppositely disposed perpendicular parallel channeled standards 2. These standards may be mounted upon a sheet metal base 3 by means of bolts, and the sheet metal base may be embedded or otherwise anchored in a suitable cement or concrete foundation 4.

The upper ends of the channeled standards are relatively reinforced by the transverse braces 5, bolted at 6 to the standards. Diagonal braces 7 are also connected to the standards, at the same junctions where the braces 5 are connected. Though the tower is mounted upon a metal base, which in turn is anchored in a concrete or cement foundation, the tower is additionally reinforced by means of the guy wires 8 and 9, which diverge downwardly, laterally and outwardly, and are connected to the foundation in any suitable manner, thereby materially reinforcing and holding the tower in a perpendicular position.

100

105

22 While the standards 2 are referred to as being channeled, they are provided with intermediate longitudinal ribs 10, which divide the standards into parallel guides or channels 11.

10 Mounted in bearings of the upper and lower parts of the standards 2 are shafts 12 and 13, and carried thereby are sprockets 14 and 15, which are engaged by the endless sprocket chains 16. These chains travel upon the outer faces of the outer flanges of the standards, and pivoted detachably on the chains at spaced intervals are panels 16a. Each panel comprises an angle iron frame 17, the upper portion of which has axially aligned pintles or journals 18. These journals or pintles 18 are mounted detachably on the chains 16. By mounting the journals or pintles 18 detachably on the chains, it is 20 possible to remove the panels, for replacement by others, or to permit the advertisement on each panel to be removed, and others attached. The advertisement may be painted on a sheet metal plate carried by the frame 17, or may be supplied on a cloth or piece of paper or any other suitable material, which in turn may be pasted at the edges to the sheet metal panels of the frames 17. The sheet metal panels 19 of the frames 17 are 30 riveted or otherwise secured to the frames, which are constructed of angle iron. The lower portion of each frame 17, which carries a panel, is provided with axially aligned lugs 20. These lugs operate in the guides 11 of the standards 2, so as to prevent the wind or other weather disturbances from vibrating the panels or frames, which would prevent the advertisement from being easily 35 read.

40 The arms 18 of the panels or frames, during their travel are upon the outer faces of the flanges of the channeled standards, whereas the lugs 20 are within the guides 11, thereby holding the frames or panels in 45 slightly inwardly inclined and downward positions, in order to permit the advertisements upon the panels to be seen from below much easier than if the panels should be hung straight or perpendicular. The arms 50 18 always remain on top and the lugs 20 at the bottoms.

55 In order to permit the arms 18 to pass at 21 and 22. Riveted to the upper and lower parts of the outer flanges 23 of the standards at diagonal opposite portions of the openings 22 are springs 24, with which 60 the arms 18 of the panels or frames engage, and then pass, by forcing the free ends of the springs open.

65 The central flange or rib 10 of each channeled standard is cut away at its upper and lower portions, to permit of the disposition

of the upper and lower shafts 12 and 13, which carry the sprockets 14 and 15. The central flange or rib 10 at its upper and lower portions below the cut away portions 26 is additionally cut away to provide the 70 openings or passages 28 and 29. The central flange adjacent the lower portion of the opening or passage 28 has riveted or otherwise secured thereto as at 30 a leaf spring 31, which closes the passage or opening 28. 75 The central flange 10 of each standard adjacent the upper part of the passage or opening 28 has an extension 32, which extends downwardly in an inclined direction, and has its lower end edge immediately adjacent 80 or secured at 33 to one of the side flanges of the standard, so that when the panels or frames are ascending, the lower lugs of the frames or panels contact with the extension 32 (which constitutes a switch), so that the 85 lower lug 20 may pass through the passage or opening 28, by riding under the spring 31. As soon as the lug 20 passes the spring 31, it assumes a position in the other channel or guide, ready to descend.

90 The central flange 10 at a point immediately adjacent the opening or passage 29 has riveted thereto as at 34 a leaf spring 35, the lower end of which engages with the lower edge of the opening or passage 29. The central flange immediately below the passage or opening 29 has an extension 36 connected thereto in any suitable manner, and is extended upwardly and inclined toward one 95 of the side flanges of the standard. The 100 upper edge of this extension 36 (which constitutes a switch) is located adjacent to or secured to one of the side flanges of the standard, so that as the lower lug 20 descends in its channel or guide, it will be deflected by the extension or switch 36 into the 105 opposite guide or channel. In passing into this opposite guide or channel, the lug 20 will pass the spring 35, by pushing its free end to one side. After the lug 20 passes the 110 free end of the spring 35, it will assume a position sufficiently below the opening or passage 29, to permit the lug 20 to ascend. From the foregoing it is obvious how the 115 arms 18 shift from the exterior of one of the side flanges of each standard to the exterior of the opposite side flange. Also it is obvious how the lugs 20 are shifted from one 120 guide or channel of each standard when ascending, to the opposite guide or channel, when descending. It will be noted that in this way the panels or frames are maintained in slightly inclined positions, so as to enable the advertisements thereon to be 125 easily read from below, and at an angle to the 130 end of the carrier.

The lower shaft 13 carries a spur gear 37, with which a pinion 38 engages. This pinion is carried by a motor shaft 39 of a motor 40, for imparting revoluble move-
